UNITED STATES PATENT OFFICE.

ARTHUR ZIMTBAUM, OF BROOKLYN, NEW YORK.

WINDOW-SILL PROVISION-BOX.

1,248,982.

Specification of Letters Patent. Patented Dec. 4, 1917.

Application filed June 6, 1917. Serial No. 173,074.

To all whom it may concern:

Be it known that I, ARTHUR ZIMTBAUM, a citizen of the United States, and a resident of Brooklyn, in the county of Kings 5 and State of New York, have invented certain new and useful Improvements in Window-Sill Provision-Boxes, of which the following is a specification.

The invention pertains to a novel construction of provision box to be mounted on a window-sill and accessible to the occupant of the room upon the raising or opening of the lower sash of the window.

The essential features of novelty present 15 in the box reside in its shape and in its manner of mounting so that the box may be conveniently employed and be of commodious nature without interfering unduly with the view from the window or the light entering the room or egress from or ingress to the room through the window.

The box will preferably be made of sheet metal and of sufficient height to contain two or more shelves, and the box has an angular 25 front containing a door which may be opened and closed at will, a curved outer wall, and an angular inner side wall adapted to engage the brick or stone wall of the building and a portion of the outer window-sill and closely fitting the angle of the said 30 wall adjacent to the window-frame. The box engages the wall of the house and the window-sill and projects outwardly beyond the window-sill and may be conveniently 35 supported in place by an iron strap fastened at one end to the upper portion of the box and at the other end to the window-frame. The box may also be secured by an inner concealed cleat through which screws 40 or the like may be passed and fastened into the window-frame from the inner side of the box. The box is of special shape in cross-section and of considerable capacity, and the door of the box is hinged at its outer edge 45 and at its inner edge, which is close to the window, may be provided with a latch whereby the door may be fastened in closed position. The door stands at an angle to the window and when swung to its open position permits of ready access to any portion 50 of the box.

The invention will be fully understood from the detailed description hereinafter presented, reference being had to the accompanying drawings, in which:

Figure 1 is a top view of the provision box

of my invention shown as applied upon a window-sill, the sill being shown partly broken away and the window frame and wall of the house being shown in horizontal 60 section;

Fig. 2 is a horizontal section through the same taken on the dotted line 2—2 of Fig. 3;

Fig. 3 is a vertical section through the box and adjacent portions of the building taken 65 on the dotted line 3—3 of Fig. 1;

Fig. 4 is a vertical section through the box taken on the dotted line 4—4 of Fig. 2, and

Fig. 5 is a detail view, partly broken away 70 and partly in section, of a portion of the inner wall of the box and illustrates the inner cleat which may be employed to assist in securing the box in rigid position on the window-sill, the section being taken on the dotted line 5—5 of Fig. 2.

In the drawings 10 designates a portion of the wall of the building, 11 the main window-sill, 12 the customary framing for the window-sashes, not shown, and 13 a customary base or sill secured upon the base 80 or sill 11 and extending transversely of the side portions of the window-frame 12.

The provision box is numbered, as a whole, 14 and comprises a vertical convexly curved 85 outer wall or side 15, an angular side 16 and an inner wall composed of the flat section 17 adapted to lie against the outer surface of the wall 10, a section 18 adapted to lie against the side edge of the wall 10 and 90 being at right angles to the section 17, and a section 19 adapted to lie against the outer face of the window frame 12, all as clearly shown in Figs. 1 and 2. The curved outer wall 15 at one edge joins the inner wall 95 section 17 and at its other edge joins what may be termed the front angular side 16 of the box, and said wall 15 comprises considerably more than a quarter circle and preferably about three-eighths of a circle 100 so that a considerable portion of the body of the receptacle lies at the side of the window, with the angular side 16 inclining inwardly toward the outer vertical side portion of the window, whereby the box becomes accessible without unduly obstructing the passage of light into the room. The angular side 16 of the box is provided with an opening 20 and a door 21 therefor, said door at its outer vertical edge being hinged, 110 as at 22, to the angular side 16 of the box, and at its other vertical edge being provided

with a suitable spring or other latch 23 by which the door may be fastened in closed position.

Within the box 14 may be provided any suitable number of shelves 24 which may be of perforated sheet metal. Above and below the door 21 I will preferably provide the front 16 with suitable ventilating openings 25.

10 The angular side 16 of the box with the door 21 standing at a corresponding angle makes it entirely convenient, when the door is opened, for the occupant of a room to reach any part of the box 14 either for 15 the purpose of placing articles therein or removing provisions therefrom, and this is one of the desirable purposes accomplished with the use of my invention. The curved wall 14 of the box permits the box to be of 20 considerable cubical capacity and at the same time creates an interior structure which can be readily reached by the user of the box without undue stretching or strain. The inner wall of the box composed of the sections 25 17, 18, 19, snugly fit against the outer face and side portions of the wall 10 and against the outer face of the window-frame, and this aids in securing the box in position in a compact manner and without undue 30 fastening devices. In the present instance I secure the box in position by means of an outer strap 26 and an inner cleat 27, the strap 26 being riveted at its outer end to the outer vertical side of the box, thence 35 extending inwardly on the top 28 of the box and thence bent vertically, as at 29, and secured to the window framing 12. The cleat 27 is at the inner side of the section 19 of the inner wall of the box and it may 40 be fastened by screws 30 to the window framing 12.

The bottom 31 of the box rests directly upon the window-sill 11, as shown in Fig. 3.

The box as a whole has been constructed 45 with the view of securing increased convenience and capacity in boxes of the character to which the invention relates, and the box may also be very conveniently and comparatively inexpensively constructed, so that 50 all having a need for boxes of this kind,

may be supplied with the same at reasonable cost. The box is durable, its major portion is removed from the view of the window, and the door is readily accessible from the window.

What I claim as my invention and desire to secure by Letters-Patent, is:

1. A vertical window-sill provision-box comprising a top, bottom, curved outer side defining a width greater than a quarter-circle, an inner wall adapted to extend along the outer face of the wall of the house, the side face of said wall at the window and the window framing, and a front wall inclining from the outer edge of the said outer wall of the box inwardly toward the side portion of the window and provided with a hinged door, said casing being adapted at one portion to rest upon the window sill and to receive means for securing the box in vertical position.

2. A vertical window-sill provision-box comprising a top, a bottom, an outer side, an inner angular wall comprising three sections adapted respectively to extend along the outer face of the wall of the house, the side face of said wall at the window and the window framing, and a front inclining inwardly from said outer side toward the side of the window and joined to said inner wall and provided with a door hinged at its outer edge, said casing being adapted at one portion to rest upon the window-sill.

3. A vertical window-sill provision-box comprising a top, a bottom, an outer side 85 extending laterally beyond both edges of the vertical side of the window, an inner angular side adapted to the side wall of the house and in part to rest upon the window-sill, and a front inclining from the outer edge of said outer side inwardly toward the side portion of the window and provided with a hinged door.

Signed at New York, in the county of New York and State of New York this 4th 95 day of June, A. D. 1917.

ARTHUR ZIMTBAUM.
